(57) **CLAIM**

The ornamental design for a dental air polisher, as shown and described.

DESCRIPTION

FIG. 1 is a top, perspective view of a dental air polisher in accordance with the present design;

FIG. 2 is a side view thereof;

FIG. 3 is a top view thereof;

FIG. 4 is a front view thereof;

FIG. 5 is a bottom view thereof; and,

FIG. 6 is a rear view thereof.

The broken lines shown in the drawings illustrate portions of the dental air polisher that form no part of the claimed design.

1 Claim, 4 Drawing Sheets
